UNITED STATES PATENT OFFICE

EDWARD A. McCORMICK, OF NEW BRUNSWICK, NEW JERSEY, ASSIGNOR TO CHICOPEE MANUFACTURING CORPORATION, OF NEW BRUNSWICK, NEW JERSEY, A CORPORATION OF MASSACHUSETTS

PACKAGE OF FACIALS

Application filed May 28, 1932. Serial No. 614,228.

The invention relates to the packaging of sheeted articles and more particularly to packages in which the sheeted goods is partly exposed and arranged for single delivery.

5 The invention more vitally is concerned with the merchandising of woven face cloths, that is to say, special cloths or handkerchiefs for use in facial treatments and intended to compete in price with the conventional face-wipe consisting of sheeted cellulosic material; and the principal object is to package them neatly in superposed order of arrangement for single dispensing and to do this in such way as not appreciably to affect the

10 price. A specific object is to provide for convexing the stacked sheets so that the uppermost may be grasped and removed without the inconvenience and vexatious annoyance of removing more than one sheet.

15 The nature, characteristic features and scope of the invention more readily will be understood from the following description taken in connection with the accompanying drawing, forming a part hereof, wherein

20 Figure 1 is a perspective view of the new package.

25 Fig. 2 is a sectional view, more particularly showing the pad for humping or convexing the contents to facilitate grasping the top sheet.

Fig. 3 is a plan view of the pad and its carrying base, the upper and middle decks of the pad being broken away to disclose the fluted, cellular or labyrinthian structure.

30 In the drawing,—5 is a carton which is or may be of generally square or rectangular form and of conventional type including end openings and complemental closures 6, and a circular display or dispensing opening 7.

35 According to my invention I introduce into the carton a stack of sheets 8 which may represent woven articles of the nature of handkerchiefs of delicate texture with a surface feel akin to the smoothness of silk and which, 40 hence, are difficult to grasp singly in their

bulk superposed order of arrangement. The problem, therefore, is to overcome the difficulty and to provide for abstraction of the goods through the display window without the hazard and vexation of withdrawing more than one facial wipe or handkerchief at a time. I solve the problem by associating with the stack of handkerchiefs a backing 9 carrying an expansible pad which is centered with respect to the display and dispensing window and bears upon the stack of goods in such way as to convex or bulge it.

It is a merit of the invention that I accomplish the stated projection and tension of the goods in such way as to make single use of the box no hardship. That is to say, the pad is formed efficiently and inexpensively of discs 10 of corrugated paper or fiber, decked or faced, as at 11, and secured as a unit, as by gluing, to the backing 9. The facing elements 11 are thin sheets of paper or the like for the purpose not only of keeping down expense but of giving full play to the expansible properties of the flutings. The described cellular or labyrinthian pad could well be secured to the inside wall of the bottom of the carton but that would add to the expense of the package and would also hamper automatic filling. Therefore, I regard it not only as the preferred embodiment but as of the essence of the invention that the pad be carried by a backing introducible into the carton along with the filling of handkerchiefs or the like.

80 What is claimed as new, is:—

1. A package, comprising a carton having a display window through which sheeted articles may be grasped and withdrawn, a filling for the carton consisting of a plurality of sheeted articles in superposed order of arrangement, and a backing for the filling having a boss-like projection in the form of a cellular pad centered with respect to the window and impinging upon the filling cen- 85 90

trally to stress the same upon the rim of the window.

2. A package, comprising a carton having a display window through which sheeted articles may be grasped and withdrawn, a filling for the carton consisting of a plurality of sheeted articles in superposed order of arrangement, and a backing for the filling carrying an expansible pad for convexing the filling in line with the window, said pad consisting of concentric discs of corrugated fiber board faced with separating decks.

In testimony whereof, I affix my signature.
EDWARD A. McCORMICK.
